DESIGN FOR A COMBINED PIPE AND SMOKING TRAY

Walter Suhr, Detroit, Mich.

Application March 15, 1935, Serial No. 55,892

Term of patent 7 years

To all whom it may concern:

Be it known that I, Walter Suhr, a citizen of the United States, residing at Detroit, in the county of Wayne and State of Michigan, have invented a new, original, and ornamental Design for a Combined Pipe and Smoking Tray, of which the following is a specification, reference being had to the accompanying drawing, forming part thereof.

Fig. 1 is a view in side elevation of a combined pipe and smoking tray, showing my new design, a section of the smoking tube of the pipe being broken away.

I claim:—

The ornamental design for a combined pipe and smoking tray as shown.

WALTER SUHR.
